CUTTING DIE FOR PRINTING PRESSES OF
THE PLATEN TYPE

William O. Crossley, Toledo, Ohio

Application February 11, 1946, Serial No. 646,809

3 Claims. (Cl. 101—408)

1

This invention relates to a combination in a printing form or plate and a die and press of the platen type in which the inking rollers do not contact the cutting or impressing die in the operation of the press, thereby avoiding cutting of the inking rollers and also avoiding inking of the die cutting edge.

An object of the invention is to provide in a machine of the class indicated, an arrangement in which a great number of different die impressing elements—such as, for example, a cutting rule, perforating, scoring, or creasing rule may be readily applied to meet the requirements for an indefinite number of printing and impressing jobs with a platen type press and includes means to carry a cutting or impressing die in such a manner as to space the die in such relation to the type when the latter is being inked by the inking rollers, that the rollers do not contact the die when inking, but when the press is operated the same acts to print and to effect a die impression in one operation of the press. This invention, therefore, relates to the position of die which is outside of the course of ink roller travel and between the platen and the press bed and separate and apart from the chase in which the usual conventional cutting die is now locked up when in use.

The object of the invention is to provide an improved cutting die adapted to be movably secured to the gripper arms of a printing press, whereby the paper or cardboard to be operated upon may be die-cut simultaneously with the printing of the same without inking the cutting die and without damage to the inking rollers.

Another object has to do with the method of securing the component operational parts of the cutting die to its flat sheet-metal base, which means is obtained by the use of a suitable adhesive, by soldering, welding, brazing, or by similar means; said means allowing for extreme maneuverability in placing into any desired position the cutting rule pieces and other related operational die parts, after forming by bending, and mounting said cutting die operational parts upon its flat sheet-metal base.

Still another object is the use of auxiliary operations such as perforating, scoring, creasing, or embossing, with die-cutting and printing, or combinations of two or more of these operations simultaneously with printing without inking the die form and without damage to the inking rollers, but allowing the inking of the printing form, and with one impression action of the printing

2

press without the use of specially prepared machined parts.

Still another object is the savings in costs usually incurred when ordering the cutting die made outside the plant, which die can now be made within a printing plant by anyone without previous experience, thus adding to the profits of the plant as well as making rush orders possible.

Still another object of this invention is the savings in production costs by the elimination of expensive equipment generally used in die construction, such as a jig saw, a rule bender, and special rule cutter. Cutting dies made by this improved method can be easily made by utilizing the regular slug cutter found in all printing shops for cutting the small special cutting rule; a vise and a pair of small nosed pliers can be used for bending or forming the cutting rule; a pair of tin shears for cutting the die sheet-metal base upon which the cutting die operational parts are secured as hereinafter set forth and the die base is secured to the gripper arms, as hereinafter described and specifically illustrated.

Another object of the invention is the accomplishment of a simple means of make-ready of the die cutting form or cutting die. Since the cutting die is readily accessible on the gripper arm, it is no longer necessary to remove the chase and apply make-ready patches behind the die block because the make-ready patches can be more easily applied and better "spotted" in the correct places by applying patches directly to the rear side or bottom of the cutting die on the die sheet-metal base. This is faster, more accurate and with care, a "kiss" impression is possible, thus adding life to the cutting die by keeping the cutting edge of the die sharp much longer.

Still another object of this invention is the possible use of these cutting dies in the ordinary die press, if desired, by tacking or otherwise securing to a wood block of predetermined height, and locking the block with the die on it in a chase and operating from the press bed as usual.

Still another object of this invention is the simple means employed for firmly but movably securing the cutting die to the gripper arm by making use of the extended portion of the cutting die sheet-metal base. This eliminates the use of specially manufactured parts requiring machine shop practice as well as the use of skilled labor in manufacturing these parts, thus reducing to a minimum the use of materials as well as labor costs. It makes unnecessary the many sizes and varied types of holders which would be necessary to hold the numerous sizes and shapes of tab cut-

ters, punches, perforators, scoring and creasing rule forms as well as the varied shapes and sizes of embossing dies, thus attaining desirable simplification and a minimum of expense.

Further objects and advantages are within the scope of this invention such as relate to the arrangement, operation, and function of the related elements of the structure, to various details of construction and to combinations of parts, elements per se, and to economies of manufacture and numerous other features as will be apparent from a consideration of the specification and drawing of a form of the invention, which may be preferred, in which:

Figure I is a diagrammatic view showing the press open and illustrating the position of my die;

Figure II is a similar view showing the press closing and the relative position of the inking rollers, die and platen;

Figure III is a view showing the press closed;

Figure IV is an enlarged horizontal cross sectional view with the press closed;

Figure V is an enlarged perspective view with the die shown in my invention;

Figure VI is a detail partly in section of one means of supporting my die;

Figure VII is a sectional view through the die and supporting plate;

Figure VIII is a perspective view of a modification in which both the printing and die operations are completed in one operation of the press in one run of the work;

Figure IX is an enlarged isometric view showing the action of the arrangement of Figure VIII.

In one embodiment of my invention, I provide a die 10 carried by one of the grippers 12 of the press as shown in Figures IV, V, VI and VII, where I have shown a platen type press with a chase 15 carried in the press bed 16, a pivoted platen 17, and the usual grippers 12 and 13.

One satisfactory die for carrying out my invention includes a carrying plate 20, bent in an offset manner as shown in Figure VI, to be suitably secured as by split rivets (see Figure VII) as indicated at 22 to the gripper 12 on one end and carry at the other end, the actual cutting or impressing rule 24 of the die itself, surrounding which is a resilient, releasing means—as a rubber work removing pad 26.

Instead of making the die 10 of the entire thickness to extend from the bed of the press to the platen when the press is closed, in my invention I use a suitable backing means 25 located on the bed and locked up in the chase 15 with the type 28 as indicated in Figure V. Then the die member 10 proper may be formed by using thin sheet metal piece 20 referred to, and the cutting or impressing rule 24 is less than the height of the type 28. This working member or cutting rule 24 is suitably secured to the metal piece or carrying plate 20. In an embodiment of my invention, the die is constructed upon or built up upon and attached to the thin flat sheet base 20 of sheet metal or other suitable material by a bonding agent of suitable material which may be solder, and I also employ brazing, welding, or the use of glue or other suitable adhesive, or any other form of bonding agent of suitable character.

In the arrangement shown in Figure IV where the press is shown in closed position, the parts are illustrated in detailed relation to each other, just having effected an impression or cut upon the material being acted upon such as paper,

cardboard, et cetera, being used in the particular job under consideration.

In Figures I, II, and III, I show diagrammatically in various positions of operation, the action of the inking rollers 30 in inking the type 28 without coming in contact with the die 10. The several parts are operated by standard press mechanisms. Figure I shows the press open where the rollers 30 are located below the press bed, having passed down from the ink carrying plate 31 at the top over the type 28 into their lower position. As the press begins to close as shown in Figure II, the rollers 30 pass upward over the type and on in Figure III, reach the top of the ink plate 31 when the press becomes fully closed as in Figure III and also in Figure IV.

In both of Figures I and II, it will be seen that when the rollers 30 pass back and forth over the press bed on the type, the die 10 is always spaced from the same. It is only when the rollers are above the chase and platen that the die 10 comes in contact with the press backing in the chase 15, and then the closing of the press causes the platen 17 to effect an impression or cutting action as shown in Figure III.

In using the die form with a printing form in the embodiment of my invention shown in Figures I to VII, I cut stock double in most cases, though not always, and then lock up printing form in one-half of the chase and blank backing material in the other half. I then place a piece of protecting sheet metal beneath the tympan under the die to protect the platen and "make ready" as usual. I proceed to print and cut all stock and reverse the stock and feed again. This gives a complete die cut and printed job 2-up of the work and turn manner. As stated before, I prepare the die form previously with an ejection means or material of rubber, cork, or other resilient material which acts to free the stock being die-cut from the cutting die after the impression.

Should the run be a short one and the ink not thoroughly dry when ready to reverse the sheet, then some glue must be put on the ejection material and a piece of coarse sandpaper or emery cloth stuck to it and let dry. Then I pull an impression and the die will cut through the sandpaper and you are ready to feed the second time. When dry, I then cut the sheet in two parts.

In the embodiment illustrated in Figures VIII and IX, I have shown means whereby the printing and die action on one single sheet is made at one operation, the printing and die operation both acting simultaneously so that the work in this case is run only once through the press. Thus, in certain classes of work, as by way of example, printing a ticket with a hole and slot die cut in the same, I provide the type form in the chase with an opening 35, slot 36, and "shape" the ticket by cut away top corners 38 and 39. In this case, the die 40 which may be carried by either gripper arm 13 is shown in Figure IX, or it can be attached from top or bottom by suitable extension arms or metal strips. Here, the die 40 has a cutting rule 41 shaped as indicated above and is secured to a metal carrying plate 43 which in turn is riveted or otherwise suitably attached to the gripper 13. The releasing rubber pad 45 can be made of other material, such as cork, or metal spring, or of any suitable material to effect the release of stock after an operation.

In Figures VIII and IX, as the press is open

when the inking occurs, the rollers will not at any time contact the die or cutting rule 41. As the press closes for an impression, the grippers, of course, move toward the stock as the platen comes up. As the grippers move toward "closed" position, the die 40 enters into the opening 35, slot 36, et cetera, and "seats" down into the base 25' of the type form 28. As the type form, et cetera, has been properly locked up in the chase and an impression is pulled on the tympan, then the die cutting form 40 is registered with this impression thus the die 40 will be properly positioned in place. Then as the platen 17 and type form 28 and die form 40 fully engage the "ticket" will be both printed upon the die cut as desired by the die 40 in the one closing operation of the press. Upon release on opening of the press, the resilient pad 45 releases the ticket or work from the die since the closing of the press has compressed the pad 45 in this operation as in the other embodiment of my invention described above.

What I claim is:

1. In a printing press having a gripper arm; a die adapted when the press is on impression to operate as a cutting, scoring, perforating or creasing rule, said die including a rule superimposed upon and firmly secured to a die carrying member by a suitable adhesive means in such a manner as to facilitate the proper positioning of the various actual operational parts of the die proper to a predetermined position; said die carrying member having a portion extended beyond the limit of the die proper to adjustably and firmly secure the die to the gripper arm, said die carrying member having holes in the extended portion thereof cooperating with receiving holes in the gripper arm and split rivets inserted therethrough to clinch the die and die base firmly to the gripper arm.

2. In a printing press of the platen type which has a pivoted movable platen, a stationary type

receiving chase, a die base member carried by the chase; a die cooperating with said base member when the press is on impression, and means to support said die comprising a sheet-metal plate upon which the operating element of the die is superimposed; said sheet-metal base forming means for adjustably attaching the same to the gripper arm by an extended portion on said sheet-metal base extending beyond the die proper; said extended portion of the sheet metal plate having openings therein cooperating with similar openings in the gripper arm and through which openings are arranged attachable and detachable means for securing said sheet metal base firmly to the gripper arm.

3. In a printing press of the bed and platen type wherein a gripper arm is pivotally mounted for movement with said platen, a removable die unit having a flat portion adapted to be attached to said gripper arm, said unit having a die supporting portion extending laterally from said flat portion, said laterally extending portion having a rule removably attached thereto and adapted to be brought into operative relation with a sheet held on said platen by said gripper arm.

WILLIAM O. CROSSLEY.
